UNITED STATES PATENT OFFICE

2,568,467

TYPOGRAPHICAL SLUG CASTING MACHINE

Richard Henry Scott, Hale, and Arthur Staniland
 Hayward, Altrincham, England, assignors to
 Linotype and Machinery Limited, London, Eng-
 land, a company of Great Britain

Application September 25, 1946, Serial No. 699,308
 In Great Britain September 26, 1945

10 Claims. (Cl. 199—47)

1

This invention relates to improvements in typographical slug casting machines of the kind known commercially under the registered trademark "Linotype," wherein a composed line of matrices is presented to the face of a slotted mould, the mouthpiece of a metal pot presented against the rear face of the mould, and molten metal injected from the metal pot through the mouthpiece into the mould slot and up against the composed line of matrices to produce a type-bar or slug.

In particular, the invention relates to an improved metal pot having a reciprocating pump plunger in a pump plunger cylinder or barrel from which metal is pumped through a communicating mouthpiece into the mould, and it is an object of the invention to provide an improved metal pot construction in which the pumping mechanism may be removed for cleaning purposes. Another object of the invention is to provide an improved metal pot construction wherein the volume of air between the pump plunger and mouthpiece is reduced and a direct, smooth, feed of metal to the mouthpiece is obtained.

According to the present invention there is provided in or for a typographical slug casting machine a metal pot having a reciprocating pump plunger in a detachable pump plunger cylinder and means whereby the pump plunger cylinder is locked in position to communicate with a delivery mouthpiece and is unlocked to allow the pump plunger cylinder to be detached and removed from the metal pot. The pump plunger may be disconnected from its operating means so that when the pump plunger cylinder is unlocked the pump plunger and pump plunger cylinder may be removed from the metal pot as a complete unit.

In one construction of metal pot according to the invention, the pump plunger cylinder is arranged in an inclined position and in line with a delivery throat connecting the pump plunger cylinder to the delivery mouthpiece, one end of the pump plunger cylinder being fitted into a seating formed in an extension of one end of the delivery throat. The pump plunger cylinder may be locked in position by cotter keys which engage between lugs on the outside of the pump plunger cylinder and slots formed in the extension of the delivery throat.

In an alternative construction of metal pot according to the invention, the pump plunger cylinder is provided with a flat seating which is detachably sealed and locked against a corresponding flat seating formed on a part of the metal pot communicating with the delivery

mouthpiece. The seating may be formed on a flange on the pump plunger cylinder, the lower portion of the flange being of wedge formation and fitted into correspondingly shaped slots in lugs fixed to the wall of the metal pot communicating with the delivery throat and mouthpiece. Preferably the flange is formed at one end of the pump plunger cylinder which is arranged in an inclined position and in line with the delivery throat and mouthpiece of the metal pot.

According to a further feature of the invention, the pump plunger cylinder communicates with the mouthpiece through a delivery throat comprising a plurality of throat sections which have been formed to correct shape out of solid metal, finished with a smooth surface on the inside and finally joined together to form the complete delivery throat.

In a further feature of the invention, the mouthpiece is provided in its front or mould-contacting face with a recess in which a porous metal tang is cast on bringing the mouthpiece into contact with a mould to cast a typographical slug. The mouthpiece may be formed with passages which on bringing the mouthpiece into contact with the mould connect the recess in the mouthpiece with recesses in the mould. Means may be provided for ejecting the metal tang from the recess and such ejecting means may be carried in the mouthpiece and operated by movement thereof into and out of contact with the mould.

The invention will be clearly understood from the following description of forms which the invention may assume and the description will be more readily followed by reference to the accompanying drawing wherein:

Figure 1 is a side elevation, partly in section, of the casting mechanism of a typographical slug casting machine embodying one form of the invention;

Figure 2 is a side elevation, partly in section, of the pump plunger cylinder and the means for locking it in position;

Figure 3 is a view similar to Figure 2, but showing the pump plunger cylinder unlocked and detached from its seating;

Figure 3a is a plan view of the metal pot shown in Figure 1, with the spring and cover removed;

Figure 4 is a side elevation, partly in section, of the casting mechanism of a typographical slug casting machine embodying an alternative form of the invention;

Figure 5 is a view showing the pump plunger cylinder and pump plunger according to Figure 4 removed from the metal pot;

Figure 6 is a view in section of the metal pot

2

from which the pump plunger cylinder and pump plunger have been removed;

Figure 7 is a plan view of the metal pot shown in Figure 4 with the spring and cover removed;

Figure 8 is a sectional view taken on the line VIII—VIII of Figure 7 with the pump plunger removed;

Figure 9 is a front view of a metal pot delivery throat according to the invention;

Figure 10 is a side elevation of the throat;

Figure 11 is a plan view of the throat;

Figure 12 is an enlarged sectional view of a metal pot mouthpiece, according to the present invention, in contact with a mould for casting a typographical slug;

Figure 13 is a view of the mouthpiece taken on the line XIII—XIII of Figure 12, and

Figure 14 is a view of part of a typographical slug showing in dotted lines a part of the porous metal tang which was cast thereon.

Referring to Figures 1, 2 and 3 of the drawings, the metal pot 1 is mounted on legs 2 and is moved by the cam 3 and cam roller 4 on the lever 5 so as to bring the delivery mouthpiece 6 of the metal pot into and out of contact with the mould 7 on the mould wheel 8. In Figure 1 the mouthpiece 6 is in contact with the mould 7 preparatory to the casting of a typographical slug. The pumping mechanism whereby molten metal is forced through the delivery throat 9 to the mouthpiece 6 comprises a pump plunger cylinder 10 in which a pump plunger 11 is reciprocated by a cam-operated lever 12 connected to the pump plunger 11 by a link 13, lever 14 and link 15. The cam-operated lever 12 may be disconnected from the lever 14 by removing the stud 16. When the stud 16 is removed, the link 13 is turned about the stud 17 and the hole 18 is brought into alignment with the hole 19 and the stud 16 inserted therebetween. The link 13 may then be used a handle for removing the pumping mechanism after the pump plunger cylinder 10 has been unlocked and detached by the means about to be described. The lever 14 is mounted on a tubular shaft 20 carried by a withdrawable shaft 21 (see Figure 3a) in bearings 22 formed in the side walls of the metal pot. The shaft 20 is provided with a stop member 23 which, in the normally retracted position of the pump plunger, is held against a bearing 22 by means of a spring 24.

The pump plunger cylinder 10 is tapered at the end as at 25 (Figure 3) to fit into a correspondingly shaped seating 26 (Figure 1) formed in an extension 27 of the delivery throat 9 attached to the front wall of the metal pot. The extension 27 is so formed that when the tapered end 25 is fitted into the seating 26 the pump plunger cylinder 10 is in an inclined position and in line with the delivery throat 9 and mouthpiece 6. The extension 27 is provided with pairs of lugs 28 and 29, the lower pair of lugs 29 being longer than the upper pair of lugs 28 in order to form guide rests for lugs 30 on either side of the pump plunger cylinder when the tapered end 25 is being fitted into or being detached from the seating 26. The ends of the lugs 29 may, if desired, be supported on brackets 31 secured to the metal pot. After the tapered end 25 has been fitted into the seating 26, the pump plunger cylinder 10 is locked in position by cotter keys 32 which are inserted in slots 28a and 29a in lugs 28 and 29 to engage the lugs 30 on the pump plunger cylinder.

To unlock and detach the pump plunger cylinder (after removing the metal pot cover 1a),

the cotter keys 32 are withdrawn and the tapered end 25 is detached and moved away from the seating (i. e. from the position shown in Figure 1 to the position shown in Figure 3) and a hooked member 33 on the pump plunger cylinder engages the tubular shaft 20. If desired, the engagement of the member 33 with the tubular shaft 20 may be assisted by a member 33a which is turned from the position shown in Figure 1 to the position shown in Figure 3. The spring 24 is detached, and the stud 16 removed, holes 18 and 19 aligned and stud 16 inserted. After the shaft 21 has been withdrawn the complete pumping mechanism may be removed from the metal pot.

In the alternative construction shown in Figures 4 to 8, the pump plunger cylinder 10 is provided at one end with a flange 34 having a flat seating 35 (Figure 5) which is detachably sealed and locked against a corresponding flat seating 36 (Figure 6) formed on the inside of the front wall of the metal pot communicating with the delivery throat 9 and mouthpiece 6. The lower portion of the flange 34 is formed with wedge-shaped parts 37 (Figure 5) which fit into correspondingly shaped slots 38 (Figure 6) in lugs 39 fixed to the metal pot. The upper portion of the flange 34 is provided with a bolt 40 slidably mounted therein and fitted with a nut 41 having tommy-holes 42.

The pump plunger cylinder 10 is secured to a bracket 43 provided with bearings 22a (Figure 7) carrying a shaft 20a on which the lever 14 is mounted. The bracket 43 is provided with a stop 44 against which a screw 45, in the lever boss 14a, and dimpled into shaft 20a, is held by a spring 24 in the retracted position of the pump plunger 11 (Figure 4). The spring 24 is connected between the lever 14 and the flange 34.

To attach and lock the pump plunger cylinder 10 and associated parts shown in Figure 5 to the metal pot shown in Figure 6, the flange 34 is inserted downwardly between the guides 46 attached to the front wall of the metal pot and the wedge-shaped parts 37 pushed into the slots 38. As the flange 34 is being inserted downwardly between the guides 46 the bolt 40 enters a slot 47 in the front wall of the metal pot. A peg 40a prevents turning of the bolt. After the wedge-shaped parts 37 have been pushed home in the slots 38 so that the seating 35 is pressed and sealed against the seating 36, the pump plunger cylinder 10 is finally locked in position by turning the nut 41. To unlock and detach the pump plunger cylinder 10, the nut 41 is loosened and the flange 34 is drawn upwardly to remove the pump plunger cylinder and pumping mechanism from the metal pot.

Referring to Figures 9 to 11, the delivery throat 9 is first made in two sections 48 and 49 which have been formed to correct shape out of solid metal. The inner surfaces 50 of the sections 48 and 49 are machined to a smooth finish so as to provide surfaces which ensure an unimpeded flow of molten metal directly to the mouthpiece 6. The inner edges of the sections 48 and 49 are bevelled as at 51. When the inner edges of the sections 48 and 49 are placed together, a V-shaped groove, extending longitudinally of the throat and along the upper side thereof, is formed, and a similar groove is formed along the underside thereof. The sections 48 and 49 are welded together along these grooves to form the complete delivery throat 9.

The mouthpiece 6 is provided in its front or

mould-contacting face with a recess 52 (see Figures 12 and 13) in which a porous metal tang 53 (Figure 14) is cast on bringing the mouthpiece 6 into contact with the mould 7 to cast a typographical slug. The recess 52 connects with vent nicks or passages 54 in the mouthpiece and on bringing the mouthpiece into contact with the mould the passages 54 connect with the recesses 55 which are provided in the mould for casting a ribbed typographical slug (Figure 14). When molten metal is pumped into the mould, air from the delivery throat and the mould is forced away from the face or matrix side of the mould to rise through the passages 54 into the recess 52. As solidification of the molten metal occurs very quickly on contacting with the cold matrices, the face of the typographical slug will be free from air holes. The last portion of metal to solidify is the metal tang 53, and as air has been driven away from the face of the mould and has risen into the recess 52 the metal tang 53 is of a porous nature.

The metal tang 53 is ejected from the recess 52 by a number of ejector rods 56 passing freely through the mouthpiece 6 (Figure 12). The ejector rods 56 are normally spring-pressed into the recess 52 by springs 57 extending between the front wall of the metal pot and collars 58 on the ejector rods. The ejector rods 56 pass freely through a plate 59 which is pivotally mounted behind the mouthpiece 6 and has an adjustable stud 60. When the metal pot is moved to bring the mouthpiece 6 into contact with the mould 7, the stud 60 contacts with the mould wheel 8 and causes the plate 59 to bear against the collars 58 to withdraw the ejector rods 56 from the recess 52 (as shown in Figure 12).

After casting, the metal pot and mouthpiece move away from the mould 7 and mould wheel 8 and the plate 59 assumes a vertical position, tending to move away from the collars 58, and allows the springs 57 to press the ejector rods 56 into the recess 52 and eject the metal tang 53. The metal tang 53 is removed from the typographical slug during the usual trimming operation and the slug is subsequently ejected from the mould.

Having described our invention, we declare that what we claim and desire to secure by Letters Patent is:

1. In or for a typographical slug casting machine the combination of a metal pot, a reciprocating pump plunger, means for operating the pump plunger, connecting means between the pump plunger and the operating means, means for disconnecting the connecting means from the operating means, a detachable pump plunger cylinder, a delivery mouthpiece, means whereby the pump plunger cylinder is locked in position to communicate with the delivery mouthpiece and is unlocked to allow the pump plunger cylinder to be removed from the metal pot, and engaging means carried by the pump plunger cylinder adapted to engage with the connecting means when the pump plunger cylinder is unlocked.

2. In or for a typographical slug casting machine the combination of a metal pot, a reciprocating pump plunger, means for operating the pump plunger, a delivery throat, a delivery mouthpiece attached to one end of the delivery throat, an extension secured to the other end of the delivery throat, a seating formed in the extension, a detachable pump plunger cylinder arranged in an inclined position in line with the delivery throat and having one end tapered to fit into the correspondingly shaped seating formed in the extension, and removable cotter keys which

engage between lugs on the outside of the pump plunger cylinder and recesses formed in extensions of the delivery throat.

3. In or for a typographical slug casting machine the combination according to claim 2 including connecting means between the reciprocating pump plunger and the means for operating the pump plunger, and a hooked member on the pump plunger cylinder for engaging with the connecting means when the cotter keys are removed.

4. In or for a typographical slug casting machine the combination of a metal pot, a reciprocating pump plunger, means for operating the pump plunger, a detachable pump plunger cylinder, a delivery mouthpiece, a delivery throat connecting the delivery mouthpiece to the front wall of the metal pot, a flange on the pump plunger cylinder, a flat seating formed on said flange, a wedge-shaped lower portion formed on said flange, lugs fixed to the wall of the metal pot having slots shaped to correspond to the wedge-shaped lower portion and into which slots the wedge-shaped portion is fitted, a flat seating formed on the inside of the front wall of the metal pot communicating with the delivery throat and means whereby said seatings are detachably sealed together.

5. In or for a typographical slug casting machine the combination of a metal pot, a reciprocating pump plunger, means for operating the pump plunger, a detachable pump plunger cylinder, a delivery mouthpiece, a delivery throat connecting the delivery mouthpiece to the front wall of the metal pot, a flange on the pump plunger cylinder, a flat seating formed on said flange, a wedge-shaped lower portion formed on said flange, lugs fixed to the wall of the metal pot having slots shaped to correspond to the wedge-shaped lower portion and into which slots the wedge-shaped portion is fitted, a flat seating formed on the inside of the front wall of the metal pot communicating with the delivery throat, and an upper portion of said flange provided with a nut and bolt slidably mounted therein and arranged so that when the lower portion of the flange is fitted into the slots in the lugs the bolt is dropped into a slot formed in the front wall of the metal pot and the nut is turned to seal said seatings together.

6. In or for a typographical slug casting machine the combination of a metal pot, a reciprocating pump plunger, means for operating the pump plunger, a detachable pump plunger cylinder, a delivery mouthpiece, a tubular shaft on which the means for operating the pump plunger is mounted, bearings in the side walls of the metal pot, and a withdrawable shaft carried in said bearings and supporting the tubular shaft.

7. In or for a typographical slug casting machine the combination of a metal pot, a reciprocating pump plunger, means for operating the pump plunger, a pump plunger cylinder, a delivery mouthpiece communicating with the pump plunger cylinder and being provided in its mould contacting face with an open tang casting recess to communicate with the mould cavity and arranged to be closed by the mould, means for moving the metal pot to bring the delivery mouthpiece into and out of contact with a mould to cast a typographical slug in the mould, spring-pressed ejector rods passing freely through the mouthpiece so as to enter the recess, collars on the ejector rods, a plate pivotally mounted behind the mouthpiece and arranged to bear against the collars on the spring-pressed ejector rods.

which pass freely through the plate and an adjustable stud carried by the plate and adapted to contact with a mould wheel so as to move the plate and withdraw the ejector rods as the mouthpiece moves into contact with the mold.

8. In or for a typographical slug casting machine, the combination of a metal pot, a reciprocating pump plunger, means for operating the pump plunger, connecting means between the pump plunger and its operating means, a detachable pump plunger cylinder, a delivery mouthpiece with which said cylinder communicates, and means for disconnecting the connecting means from the plunger operating means and for connecting said connecting means to the pump plunger cylinder, whereby the pump plunger and cylinder may be removed from the metal pot as a complete unit.

9. In or for a typographical slug casting machine, the combination of a metal pot, a reciprocating pump plunger, means for operating the pump plunger, connecting means between the pump plunger and its operating means, a detachable pump plunger cylinder, a delivery mouthpiece with which said cylinder communicates, means for mounting the connecting means on the detachable pump plunger cylinder, and means for disconnecting said connecting means from the plunger operating means, whereby said cylinder, pump plunger and connecting means may be removed from the pot as a complete unit.

10. In or for a typographical slug casting ma-

chine, the combination of a metal pot, a reciprocating pump plunger, means for operating the pump plunger, a pivoted lever connecting the pump plunger and its operating means, means for disconnecting the said lever from its operating means, a detachable pump plunger cylinder, a delivery mouthpiece with which said cylinder communicates, a bracket secured to the pump plunger cylinder, bearings formed in said bracket and a shaft carried in the bearings and upon which said pivoted connecting lever is mounted, whereby the pump plunger cylinder, pump plunger and connecting lever may be removed from the pot as a complete unit.
